UNITED STATES PATENT OFFICE

GEORGE B. CROUSE, OF WOODCLIFF, NEW JERSEY, ASSIGNOR, BY MESNE ASSIGNMENTS, TO BYRNES, TOWNSEND & POTTER, OF WASHINGTON, D. C., A FIRM CONSISTING OF CHARLES H. POTTER, JAMES F. PIERCE, AND RICHARD L. SCHEFFLER

ELIMINATING EFFECTS OF VARIATIONS IN CURRENT SUPPLIED TO AUDIONS

Application filed December 27, 1926. Serial No. 157,311.

This application is a continuation in part of my co-pending application Ser. No. 733,558, filed August 22, 1924, Eliminating effects of variations in currents supplied to audions, and relates to methods of and apparatus for eliminating in the output circuit of an audion the effects of variations in current supplied to one or more of its elements.

Recognizing the desirability and advantages of being able to supply the audions of a radio receiver directly from lighting circuits without the use of batteries, many inventors have obtained patents for arrangements intended to accomplish this purpose, but for one reason or another none of the patented arrangements with which I am familiar provides a current supply which is absolutely free from all alternating current components or short period variations, such as is required for the satisfactory operation of audions, particularly when used as detectors and as amplifiers in radio receivers. It is therefore the usual practice to supply the current for the audions of radio receivers from primary or secondary batteries, but their disadvantages are many and well known, particularly to those who have had occasion to use them.

When using rectified and filtered alternating current on the filaments or plates in audio-amplifiers it is frequently found that a perfection of filtering sufficient for quiet operation with one stage will not be suitable when several stages are cascaded. This, of course, is due to the fact that the ripple occurring in the first stage audion, (in a radio receiver, the detector tube) while inaudible in the output of that tube, will be amplified through succeeding stages to cause an objectionable disturbance.

In accordance with this invention the disturbance which arises in the output circuit and is due to the energizing of an element of the audion from a source of a direct current having alternating components is reduced or eliminated by impressing upon another element of the audion a ripple voltage which is derived from the same source of energy and is so adjusted as to magnitude and phase that its effect on the output circuit

counteracts the disturbing effect of the current applied to the first element. The invention may be practiced in two general ways. The direct current having alternating components may be used to energize both the filament and the plate circuits of the audion, and the effects in the output circuit of the alternating components may be eliminated by a suitable adjustment of the magnitude and phase of the alternating components impressed upon the separate elements. Alternatively, the source of direct current having alternating components may be employed to energize but one element of the audion and the disturbing effects thereof may be counteracted by impressing upon another element a ripple voltage derived from the same source and suitably adjusted as to phase and magnitude.

With either general method, several specific methods are available for carrying out the invention. A disturbance in the output circuit due to variations in the current supplied to the filament may be eliminated by the application to the grid or to the plate of an alternating voltage of proper phase and magnitude. When the disturbance arises from the application to the plate circuit of a current having alternating components, the effects thereof may be opposed by the application to the grid or to the filament of an alternating voltage of proper phase and magnitude. When both the plate and filament are energized from a common source, the energizing circuits may be so designed that the effects in the output circuit of the ripple voltages applied to the separate elements will counteract each other.

An object of the invention is to provide a method of and apparatus for reducing or eliminating from the output circuit of an audion, effects of residual ripple in the current supplied to the filament and/or plate. An object is to provide a method of and apparatus for energizing an element of an audion from a source of direct current having alternating components, in which a counter electromotive force of proper magnitude and phase is applied to one of the other elements of the audion, the counter electromotive force

being taken from the source which tends to create the disturbance, and being automatically maintained in proper value both as to phase and magnitude. A further object is to provide methods and apparatus for eliminating the effects in the output circuit of an alternating component in the current supplied to the filament. More specifically, an object is to provide methods and apparatus in accordance with the object last stated, in which the disturbing effects are eliminated by impressing upon the plate circuit an alternating voltage to produce in that circuit a ripple effect opposing that due to the presence of alternating components in the filament current.

The particular nature of the invention will appear most clearly from a description of certain preferred embodiments and their applications to radio receivers as shown in the accompanying drawings in which:

Fig. 1 is an electrical diagram of an audion circuit in which the filament and plate are energized from the same source;

Fig. 2 shows the potential characteristics of the current supplied to the circuits of Fig. 1;

Fig. 3 is an electrical diagram similar to that of Fig. 1, but with additional elements in accordance with one embodiment of the invention;

Fig. 4 is a similar diagram in accordance with another embodiment of the invention;

Fig. 5 is a similar diagram in accordance with a third embodiment of the invention;

Figs. 6 and 7 are electrical diagrams of audion circuits in which only the filament is energized from the source having alternating components;

Figs. 8A and 8B are vector diagrams illustrating the relationship of the alternating voltages established in the circuit of Fig. 7;

Fig. 9 is an electrical diagram of an audion circuit in which both the filament and plate are supplied with rectified and filtered current from a common source, but only the plate circuit filter is effective to remove all alternating components;

Fig. 10 is a diagram of an audion circuit in which only the plate circuit is energized from a source having alternating components, and

Fig. 11 is a vector diagram illustrating the relation of the voltages established in the circuit of Fig. 10.

For convenience the general principles of the invention will be explained in connection with the simplified diagrams of one or more audion stages as the various applications of the invention to radio receivers will be apparent therefrom.

For the purpose of illustrating a current supply containing ripples or short period variations there is shown in Fig. 1 a battery 1 of suitable voltage for operating the plate

circuit of an audion and in series with this source of direct current there is an alternating current generator 2. The potential supplied at the terminals 3 and 4 will therefore have the characteristics shown in Fig. 2, consisting of a direct current component represented by the straight broken line A and an alternating current component represented by the solid wavy line B. The present invention contemplates the elimination from the output circuit of the ripple effect which would be produced if this alternating component B were impressed upon the known forms of audion circuits.

The audion is shown as comprising the usual three-element vacuum tube having a filament 5, a grid 6 and plate 7. The filament is connected to the source terminals 3, 4 through a resistance 8 of such magnitude as to reduce the potential across the filament to a suitable value. The secondary winding 9 of a suitable input transformer having a primary 9a is connected in the usual way with one end to the grid 6 and the other end to, say, the positive end of the filament 5. The plate 7 is connected to the positive terminal 3 through a device 10 which is shown as a telephone receiver, but it may be the primary of a repeater for connecting the output circuit to a second audion.

Since the potential applied to the terminals 3 and 4 has an alternating current component (B, Fig. 2), the current passing through the filament will also have an alternating current component, which will be in phase with the potential, since the filament circuit is entirely resistive. The alternating potential across the filament itself, which will only be a small fraction of that across the terminals 3 and 4 since a large part of it is dissipated across the resistance 8 will cause a voltage to be applied to the grid in phase with the drop, since the grid is connected to one end of the filament. A variation of the plate current of the audion will therefore occur, which will be an exact reproduction (neglecting the small distortion effects of the audion) of the alternating potential across the filament, but will be 180° out of phase with it. The alternating potential at the terminals 3 and 4 is applied directly to the plate circuit and will cause a variation in the plate current which is in phase with the potential, except for the phase shift caused by the inductive device 10.

The effect of the filament variations on the plate current due to the action of the grid will generally be smaller than the direct effect of the variations applied to the plate, as may be seen by applying some usual values to the quantities. Let

E_f = filament voltage drop, D. C. = 5 volts.

R_f = filament resistance = 20 ohms.

E_p = plate voltage, D. C. = 100 volts.

X_p = plate impedance = 20,000 ohms.

130

X_c = impedance of device 10, at frequency of ripple = 20,000 ohms.

μ = amplifying constant of audion = 9.

R_8 = resistance of 8 = 380 ohms.

5 E_b = value of alternating current potential at terminals 3 and 4 = 1 volt.

The alternating current potential across the filament, E_{bf} , will be given by the formula

$$39 \quad E_b \left(\frac{R_f}{R_f + R_8} \right) \mu$$

Since approximately only half of this potential is effectively applied to the grid, the effect on the output or plate circuit is equivalent to a voltage on the plate of

$$\frac{1}{2} E_b \frac{R_f}{R_f + R_8} \mu$$

29 (see Van der Bihl, "Thermionic vacuum tubes", page 150 et seq.).

By substituting the numerical values given above in this equation, there is obtained a value of the plate voltage fluctuation due to the filament of 0.225 volts, whereas, as stated previously, an alternating potential of 1 volt is applied directly to the plate, but in opposite phase to the filament effect.

In order that there shall be no alternating current component in the output, the alternating potential applied directly to the plate must be made equal to the plate voltage variations due to the filament effect, that is, to 0.225 volts for the electrical constants given above.

37 This may be done in several ways. One means of conveniently accomplishing it is shown in Fig. 3 which is similar to Fig. 1 (as far as elements 1 to 10 inclusive are concerned), but an inductance 11, a capacity 12 and a resistance 13 are added to the plate circuit. The relative values of the capacity and inductance are such as to make the combination anti-resonant at the frequency of the alternating component of the supply.

48 This combination, if properly designed as to internal losses, will reduce the alternating component of the plate supply to a value considerably below the value of the plate voltage fluctuations due to the filament effect without shifting its phase. The value can then be increased by the resistance 13 to that necessary to give zero alternating current in the output of the tube. When this adjustment is properly made, the plate circuit of

59 the audion has an effective impedance of infinity for the frequency of the supply ripple, and therefore there is no phase shift effect due to the inductive device 10. Since in practice, the frequency of the supply ripple is usually low, the condenser 12 serves as a by-pass for the higher useful signal frequencies and prevents intercoupling at these frequencies.

65 Another arrangement by which the invention may be practiced is shown in Fig. 4, in

which the parts identical with those of Fig. 1 are identically numbered. In this case, the resistance 8 in series with the filament is bypassed by means of the condenser 14. The effect of this capacity is to increase the filament effect, instead of, as in the case of Fig. 3, reducing the plate effect. In order that there shall be no phase shift between the filament and plate effects, this capacity by-pass circuit is made resonant at the frequency of the supply ripple, by means of the inductance 16. The amount of current by-passed is adjusted by means of the resistance 15.

Still another way in which the invention may be practiced is shown in Fig. 5, in which again the parts identical with those of Fig. 1 are similarly numbered. In this arrangement the filament effect is increased sufficiently to cancel the plate effect of the supply ripple by applying to the grid an additional alternating potential, by means of the coil 17 placed in series with the filament lead and inductively related to the input coil 9 in the grid circuit. The bracket in this figure indicates that the primary coil 9a of the transformer is also inductively related to the secondary coil 9.

The above explanation in connection with Figs. 3, 4 and 5 shows three ways in which the invention may be practiced, in the first of which the balance is obtained by reducing the plate circuit ripple; in the second, by increasing the alternating potential drop across the filament; and in the third, by increasing the filament effect by means of the grid. It should be understood that in the numerical example given and in the embodiments shown, values have been taken for the quantities, which are usual for small tubes. In the case of tubes having a high amplification constant, or having a high filament resistance, and a low value direct current plate potential, so that the filament effect will normally be greater than the plate effect, modifications of the arrangements shown will readily suggest themselves to those skilled in the art to which the invention relates.

The circuits as above described illustrate the general method of practicing the invention when energizing both the filament and the plate from the same source by an adjustment of the ripple effects due to alternating components supplied to the separate elements. The invention may be practiced in an analogous manner when alternating components are present in the source supplying only one of these elements by impressing upon the other element a suitable ripple voltage which is derived from the same source.

Fig. 6 is a circuit diagram illustrating an audion detector feeding into an audio amplifier, the filaments being energized by rectified alternating current and the plates being energized by substantially pure direct current. The input circuit of the detector includes the

grid resistance 18, grid condenser 19, and the secondary 20 of an input transformer. The output circuit comprises the primary of an audio transformer T and a suitable portion 65 of the plate battery 21.

The filaments of the detector and amplifier are energized from a source of alternating current 22 through rectifier 23 and filter 24. The filter 24 is of such design and construction 10 that the output current has alternating components of sufficient magnitude to produce ripple effects in the output circuit of a detector tube. To reduce or eliminate these effects, compensating voltage is applied to the 15 grid by a transformer whose primary 25 is connected directly across the filament and whose secondary 26 is in series in the grid circuit. To reduce the loss of direct current, the primary winding 25 has a relatively high resistance, and to allow a free path for radio 20 frequency currents a small condenser 27 is shunted across the secondary. The transformer is so constructed and arranged that its output voltage is equal to the effective 25 alternating voltage in the grid circuit due to the filament ripple, and is of opposite phase.

The compensating ripple voltage may be impressed upon the plate by a circuit such as shown in Fig. 7. The general construction 30 of the detector and amplifier circuits may be substantially identical with that shown in Fig. 6 and corresponding elements in the two views are therefore identified by the same numerals. In the circuit of Fig. 7 the lower 35 side of the input circuit is connected to the filament and a resistance 28 across which the compensating potential is impressed is made a series element of the plate circuit.

The filament current is derived from a 40 source of alternating current through a transformer having two secondary windings 29 across which the two rectifiers 29' are connected in the usual manner. The filter system which is shown for illustrative purposes 45 is of the type described in my copending application Ser. No. 130,252, filed August 19, 1926. The filter includes a choke coil 30 in series in the positive side of the line, and following the choke a pair of resistances 31 and 32 in series across the line. The primary 33 of an auto transformer is connected across the resistance 31 and the secondary 34 is connected through a second series choke 35 and through the filaments to the negative side of 50 the line. To apply the compensating voltage to the plate circuit, a connection is made from the plate end of resistance 28 to a point on the cross-resistance 31-32 through a condenser 37.

60 The manner in which the circuit of Fig. 7 corrects for the residual ripple in the filament circuit may be best understood by reference to the vector diagrams, Figs. 8A and 8B.

Let I_{20} represent the alternating current 65 flowing in the grid circuit due to the residue

of ripple in the filament. When this vector is positive, the grid is positive. Then the voltage existing across the space between filament and grid will be in phase with I_{20} and may be represented by E_1 . There is a further drop in this circuit occasioned by the complex impedance of the grid leak 18 and condenser 19. The current through this complex impedance will divide, the part I_1 through the resistance, lagging the part I_2 through the condenser. The voltage will be in phase with I_1 , as shown at E_2 . Then the vector sum of E_1 and E_2 represents the effective value of the ripple voltage applied in the grid circuit. This voltage, E_3 , is approximately one-half 80 the value of the alternating current drop across the total filament.

Now the voltage E_1 applied to the grid causes a voltage μE_1 (where μ is the voltage amplification constant of the tube) and of identical phase with E_1 (since a more positive grid means an increase of plate current). This voltage in the plate circuit is represented by E_4 in Fig. 8B, which diagram is made on a reduced scale to bring the diagram within the limits of the sheet. Returning to the first diagram, the voltage E_3 has its source in the voltage across the filter resistance 32, and since between the filament and the resistance 32 there is a large inductive reactance (coils 34 and 35), the drop across resistance 32 may be represented by a very long vector, whose direction will be almost at right angles to E_3 and whose length will be beyond the limits of the diagram, as shown by the line E_5 . This voltage E_5 is represented in direction again in the second diagram.

Now the problem requires that a compensating voltage E_6 , equal and opposite to the ripple voltage E_4 , shall be set up in the plate circuit, which compensating voltage must be derived from E_5 . A close approximation to the solution will be obtained by the use of a high condensive reactance, as condenser 37, which will cause a voltage drop approximately at right angles to E_5 , as E_7 , the magnitude of which may be adjusted by the slider on the resistance 32. The compensation obtained by the arrangement shown will ordinarily be close enough for practical purposes, but if closer results are desired, it is only necessary to substitute a complex impedance of proper characteristics for the resistance 28, as will be readily understood by one skilled in the art.

Although the apparatus shown in Fig. 7 will compensate for only a single frequency, it has been found that with the type of filters suitable for supplying the filaments of audions, only one frequency in the output is of sufficient magnitude to require any special means of suppression. It will also be apparent from the vector diagrams that any desired degree of compensation may be effected.

by a proper selection of the constants and character of the compensating impedances.

It may be desirable in some cases to replace the condensive reactance 37 by inductive or resistive reactance, or combinations of any or all of them. By constructing a scale diagram of the character above, for the particular constants of the filter and audion connections, one may determine the character and value of impedances to be employed.

When a rectifier and filter are used to supply the plate current for audion tubes, the potentiometer ordinarily used to take off intermediate direct current voltages may be used to replace the resistance 32, as shown in Fig. 9. In this figure, the several elements of the detector and amplifier circuits which are identical with corresponding elements of Figs. 6 and 7 are identified by the same numerals. The filter for the rectified current supplied to the filaments is of a well known type comprising the series inductances 40, 41, between which a resistance 42 is connected across the line. As before, it is assumed that the residual ripple passed by this filter will cause a disturbance in the detector tube output circuit but will be without substantial effect in the amplifier stages.

The plate supply is illustrated as a combined rectifier and filter of the type shown in my copending application Ser. No. 130, 252. A primary 43 of a transformer having a core 44 is connected across the alternating current source, and the terminals of the secondary winding 45 are connected to the common negative wire 46 and through a rectifier 47 to the positive output wire 48, respectively. The filter comprises the condensers 49, 50 and 51, the mutual reactance coil 52 and the choke coil 53. Since it is usually necessary to supply a number of different direct current voltages for the different audions used in a radio receiver or amplifier, a potentiometer 54 is connected across the output of the filter. The plate potential of the detector audion is taken off of this potentiometer at the point 55.

A condenser 56 is connected between a point on the resistance 42 of the filament current filter and a point on the potentiometer 55. It will be seen that this condenser is the equivalent of the condenser 37 of Fig. 7 and that that portion of the potentiometer between the point of connection of this condenser and the negative wire 46 is equivalent to the resistance 36 of Fig. 7. Vector diagrams similar to Figs. 8A, 8B, may be constructed to fit the circuit conditions of Fig. 9. Although the plate current is taken from an alternating current source, it is assumed that the output from the plate current filter is substantially free from alternating components.

In Fig. 10, I have illustrated an arrangement for correcting for alternating compo-

nents in the plate supply. As is indicated by the same reference numerals as in Fig. 9, the general construction of the radio and audio circuits, and of the plate current supply may be substantially the same as in Fig. 9. In the circuit of Fig. 10, however, the detector filament is energized from a battery 60 and the compensating ripple voltage is introduced into the grid circuit through the filament. The secondary 61 of a transformer having an iron core 62 is introduced into the filament circuit, the primary of this transformer, 63, is connected across the output of the filter (i. e. across the terminals of the potentiometer 54). A resistance 64 is included in series with the primary 63 for controlling the magnitude of the compensating voltage.

The manner in which compensation is effected in this circuit may best be understood by reference to the vector diagram, Fig. 11.

As before, let I_{20} be the alternating current ripple current flowing in the grid-filament circuit (transferred to this circuit by the voltage across the filament set up by the secondary 61). Let E_1 be the voltage between the grid and filament. I_1 and I_2 are respectively the currents through the grid leak 11 and condenser 12, and the voltage E_2 is the drop across this complex impedance. The vector combination of E_1 and E_2 gives, as before, one-half the total alternating current voltage across the filament, represented by E_3 .

To effect perfect compensation, there must be present in the plate circuit a voltage μE_1 and of opposite phase to E_1 . This voltage is shown as E_6 , and is directly derived from the drop across the resistance 54. The analysis need not be carried further to show that approximate compensation may be obtained by applying the voltage drop across 54 (which is in phase with E_6) to the filament circuit, via the transformer 61—62—63, and that if exact compensation is desired, it may be obtained by the use of a complex impedance in place of the resistance 64.

For the purpose of illustration, I have shown circuits in which the compensating voltage was applied in a single amplifying stage, but it will be apparent that the invention may be practiced in other ways. When the alternating components are comparatively weak, a correction applied at the detector tube may be sufficient to eliminate all objectionable effects of the ripple. When the residual ripple components are stronger, compensation may be necessary in other stages of the amplifier and similarly, when the ripple is exceedingly weak, a compensation applied in one of the audio stages may be adequate. The radio and audio circuits of the receiver or amplifier form no part of the invention and may take any suitable form.

I claim:

1. In the energization of a plurality of the

- circuits of an audion from a source of direct current containing periodic alternating components of audible frequency, the method of suppressing the effects of such alternating components which comprises energizing one of said circuits with direct current from said source and containing such alternating components in the ratio in which they are present in said source, and energizing another of said audion circuits with direct current from said source and containing alternating components in a ratio different from that in which said components are present in said source.
2. In the energization of a plurality of the circuits of an audion from a source of direct current containing periodic alternating components of audible frequency, the method of suppressing the effects of such alternating components which comprises employing in said circuits direct current from said source to establish the required direct current potentials upon the respective audion elements included therein and varying the relative magnitudes of the direct and alternating potentials which said source impresses upon one of said elements to thereby maintain said element at the required direct current potential while impressing thereon an alternating potential to suppress the effects of the alternating components.
3. The method of operating an audion having a cathode, a plate and a grid, which comprises applying to two of said elements from a common source of direct current containing alternating components two potentials of such relative values as to establish on said elements the direct current potentials required for operation of said audion, and independently of said established direct current potentials adjusting the relative magnitudes of the alternating potentials established on said elements by said source to thereby render their combined effects upon the output circuit substantially zero.
4. The method of operating an audion from a source of direct current containing alternating components of audible frequency, which comprises energizing one of the circuits of said audion from said source to establish in said circuit the direct current potential required for operation of said audion, and independently of the relative direct current potentials thereby established on the audion elements by said source impressing upon another circuit of the audion an alternating voltage effective to suppress the effects in the output circuit of alternating components incidentally present in said first circuit.
5. In the operation of an audion amplifier stage having an input circuit, an output circuit and a cathode-heating circuit, the cathode-heating circuit being energized and the direct current grid bias being derived from a source of direct current having alternating components of audible frequency, the method which comprises impressing upon one of the other circuits an alternating voltage of a phase and magnitude to counteract in the plate circuit the effects of the alternating components in the cathode-energizing current.
6. The method as set forth in claim 5, wherein said alternating voltage is applied to the plate circuit.
7. In the operation of an audion amplifier stage having an input circuit, a plate circuit and a cathode heating circuit, the cathode heating circuit being energized and the grid bias being derived from a source of direct current having alternating components of audible frequency, the method which comprises energizing said plate circuit from a source of substantially pure direct current, and superposing upon said plate-energizing current an alternating voltage of a phase and magnitude to counteract in the plate circuit the effects of the alternating components in the cathode-heating current.
8. In the operation of a plurality of cascaded audion stages, the method which comprises determining the direct current potential of an element of each of the audions with reference to another element of the respective audions by a common source of direct current containing periodic alternating components of audible frequency, and suppressing the effects of such alternating components in the output circuit of said cascaded stages by reactively coupling said source to but one circuit of only one of said stages, an alternating voltage derived from said source and of a phase and magnitude effective to eliminate disturbing ripple effects from the output of said cascaded stages.
9. In the operation of cascaded stages comprising an audion detector and an audio amplifier from a source of direct current having alternating components of audible frequency, the method of eliminating the effects of said components of the energizing current which comprises compensating for said effects in only the detector stage by supplying to a circuit thereof an alternating current additional to said energizing current.
10. In the operation of cascaded audion detector and amplifier stages, the method which comprises energizing the cathode-heating circuits of said stages from a source of direct current having alternating components of audible frequency, and impressing upon another circuit of said detector stage an alternating voltage counteracting the effect in the output circuit of said cascaded stages of the alternating components in the cathode-heating circuits.
11. The method as set forth in claim 10, wherein said alternating voltage is impressed upon the plate circuit of the detector stage.

12. In apparatus for energizing an audion having a grid circuit, a cathode-heating circuit and a plate circuit, the combination with means for energizing one of said circuits from a source of direct current having alternating components of audible frequency, of means operable independent of the direct current potentials impressed upon said circuits for establishing in another circuit of 5 said audion an alternating current of phase and magnitude counteracting in the plate circuit the effects of the alternating components in the said source. 10
13. The combination with apparatus for energizing one circuit of an audion amplifier stage from a source of substantially pure direct current, and another circuit thereof from a source of direct current having alternating components of audible frequency, of means 15 for establishing in said first circuit an alternating current free from all direct current components and derived from said second source to counteract the effect in the space current circuit of the stage of the alternating components in current supplied to said second circuit. 20
14. Apparatus for energizing an audion, comprising a filament current supply derived from a source of direct current having alternating components, and reactive means 25 for impressing upon the plate an alternating voltage derived from said source and free from direct current components, the impedance of said means being such that the phase and magnitude of the applied voltage produces a neutralization in the plate circuit of 30 the effects of the alternating components of the filament supply. 25
15. In apparatus for energizing an audion, a source for supplying to the filament circuit direct current containing alternating components, a plate circuit including a current supply connected between said filament and the audion plate, an impedance across 35 which said filament source establishes an alternating voltage, and circuit elements for connecting said impedance to the plate circuit of said audion to impress therein an alternating voltage free from direct current 40 components for counteracting the effects in said plate circuit of alternating components in said filament circuit. 50
16. The combination with apparatus for energizing circuits of a plurality of cascaded audion amplifier stages from a source of direct current having alternating components, of means for impressing upon a circuit of one of said stages an alternating voltage derived from said source, free from direct current 55 components and of a phase and magnitude to neutralize the effect in the output circuit of the cascaded stages of the alternating components of said source current. 60
17. In apparatus for energizing an audion from a source of direct current containing 65 periodic alternating components of audible frequency, the combination with means defining direct current paths for impressing upon the respective audion elements from said source the direct current potentials required 70 for operation of the audion, of alternating current impedance in one of said paths for altering the ratio of the alternating to direct components in the current supplied by the said path to said audion to render negligible 75 the effect of alternating components in the current supplied through the other direct current paths. 80
18. In a network of an audion stage, the combination with a plurality of sources of direct current incorporated in said network to determine the relative direct current potentials of the grid, cathode and anode of the audion, one of said sources containing periodic alternating components of audible frequency, of a corrective alternating current impedance coupling said last mentioned source with a circuit not energized thereby with direct current to impress thereon an alternating voltage free from a direct current 85 component. 90
19. In a system of cascaded audion amplifier stages including a detector and an audio amplifier, the combination with a source of direct current containing periodic alternating components of audible frequency, connected to the filament circuits of the audions for heating the same, and a source of direct current for energizing the plate circuits of 95 said audions, of an impedance path conductive for alternating current and non-conductive for direct current connected between the circuits associated with said two sources of direct current for impressing upon said plate 100 circuits an alternating voltage to suppress the effects of alternating components in said filament circuit supply. 105
20. In apparatus for energizing a plurality of the circuits of an audion from a common source of direct current containing periodic alternating components of audible frequency, the combination with circuit elements connecting said plurality of circuits to said source to establish in said circuits, the respective direct current potentials required for operation of said audion, and means for adjusting the magnitude of the alternating potential established in one of said circuits by said source to such value that the effect upon the output circuit of such alternating components is substantially zero. 110
21. In the network of an audion stage, a cathode circuit, a plate circuit, separate sources of direct current for energizing said plate and cathode circuits, a grid circuit terminating on such point in said cathode circuit that the direct current bias required for operation of the audion is obtained by the potential drop in said cathode circuit, one of 115 said direct current sources containing peri- 120

odic alternating components of audible frequency, and means for establishing in an audion circuit other than that energized by said last mentioned source, an alternating potential effective to suppress the effects of said alternating components.

22. In apparatus for supplying power to an audion from a source of alternating current, the combination with a rectifier for converting said alternating current into direct current, and a filter network connecting said rectifier to one of the circuits of said audion

to pass filtered direct current thereto, of means for impressing upon another circuit of said audion a neutralizing alternating voltage derived from said source, said neutralizing voltage being substantially free from direct current components and of a phase and magnitude to substantially suppress the effects of alternating current components passed to said first circuit by said filter network.

GEORGE B. CROUSE.
